RAILWAY SIGNALING

Filed Oct. 31, 1929

UNITED STATES PATENT OFFICE

HENRY S. YOUNG, OF WILKINSBURG, AND CHARLES A. BROOKS, OF SWISSVALE, PENNSYLVANIA, ASSIGNORS TO THE UNION SWITCH & SIGNAL COMPANY, OF SWISSVALE, PENNSYLVANIA, A CORPORATION OF PENNSYLVANIA

RAILWAY SIGNALING

Application filed October 31, 1929. Serial No. 403,739.

Our invention relates to railway signaling systems for single track railways, and has for an object the provision of means for expediting the handling of traffic at the passing sidings which are customarily provided on railways of that character.

We will describe one form of system embodying our invention, and will then point out the novel features thereof in claims.

The accompanying drawing is a diagrammatic view showing one form of system embodying our invention.

Referring to the drawing, the reference characters 1 and 1^a designate the track rails of a stretch of single track over which traffic moves in both directions, which stretch is provided with a passing siding A. The rails are divided by insulated joints 2 to form a main track section X—Y, in which the siding A is included, an approach track section W—X at one end of the siding, and another approach section Y—Z at the other end of the siding. Track section X—Y is provided with a track circuit comprising a battery 3 connected across the rails at the intermediate point in the section, and two track relays T² and T³ connected with the rails at the opposite ends of the section respectively. The approach section W—X is provided with a similar track circuit comprising a battery 3 and a track relay T¹, while the other approach section Y—Z is provided with a similar track circuit comprising a battery 3 and a track relay T⁴.

Traffic into the siding A moving from left to right is governed by a signal S^X comprising a proceed lamp G, a caution lamp Y, and a stop lamp R. Traffic into this siding moving from right to left is governed by a similar signal S^Y. Signal S^X is controlled by a line relay H², while signal S^Y is controlled by a line relay H³, both of which relays are of the polarized type, so that they are responsive to the polarity of the current by which they are energized.

Line relay H² is provided with a repeater relay R², while line relay H³ is provided with a repeater relay R³. Associated with the track relay T¹ is a line relay H¹, which relay in turn controls a pole-changing relay P¹. 50 Similarly associated with a track relay T⁴ is a line relay H⁴ which controls a pole-changing relay P⁴.

Line relay H¹ is controlled by a front contact 5 of track relay T¹, and by other apparatus to the left of point W in accordance with standard absolute permissive block signal practice for single track railways. In so far as the present disclosure is concerned, the only important factor as to relay H¹ is the 60 fact that it is energized or de-energized according as track relay T¹ is energized or de-energized. Line relay H⁴ is controlled in a similar manner by a front contact 23 of track relay T⁴. 65

Pole-changing relay P¹ is provided with a circuit which passes from terminal B of a suitable source of current, through front contact 6 of relay H¹, and the winding of relay P¹ to terminal O of the same source 70 of current. It follows that relay P¹ is energized or de-energized according as relay H¹ is energized or de-energized. Pole-changing relay P⁴ is controlled in a similar manner by a front contact 24 of line relay H⁴. Repeater relay R² is controlled by a front contact 11 of relay H², the circuit being obvious from the drawing. Repeater relay R³ is controlled in a similar manner by front contact 18 of relay H³. 75

The repeater relays R and the pole-changing relays P, are preferably all slow-releasing in character.

Line relay H³ is provided with a normal circuit which passes from terminal B, 85 through the front point of contact 8 of relay P¹, front point of contact 4 of track relay T¹, front contact 9 of track relay T², front contact 16 of track relay T³, winding of relay H³, and the front point of contact 7 of 90

relay P^1 to terminal O. When this circuit is closed, current of normal polarity is supplied to this circuit, so that relay H^3 is energized in normal direction, whereby its polar contact 19 is swung to the left. When relay P^1 is de-energized, and all other contacts in the circuit for relay H^3 are closed, the circuit is the same as before except that current of reverse polarity is supplied to relay H^3 , in which event its polar contact 19 is swung to the right. Relay H^3 is provided with an auxiliary circuit which is closed when track relay T^1 and repeater relay R^2 are both de-energized, in which event, of course, pole-changing relay P^1 is also de-energized. This auxiliary circuit is from terminal B, through back point of contact 7 of relay P^1 , winding of relay H^3 , track relay contacts 16 and 9, back point of contact 4 of track relay T^1 , back contact 13 of relay R^2 , and the back point of contact 8 of relay P^1 to terminal O. When this circuit is closed, relay H^3 is energized by current of reverse polarity.

Line relay H^2 is provided with a similar main circuit which passes from terminal B, through front point of contact 25 of relay P^4 , front point of contact 22 of track relay T^4 , contact 15 of track relay T^3 , contact 10 of track relay T^2 , winding of relay H^2 , and the front point of contact 26 of relay P^4 to terminal O. Relay H^2 is provided with an auxiliary circuit which passes from terminal B, through the back point of contact 26 of relay P^4 , winding of relay H^2 , contact 10 of track relay T^2 , contact 15 of track relay T^3 , back point of contact 22 of track relay T^4 , back contact 20 of track relay R^3 , back contact 17 of relay H^3 , and the back point of contact 25 of relay P^4 to terminal O. This circuit corresponds to the auxiliary circuit for relay H^3 except that it includes a back contact 17 of relay H^3 , whereas the auxiliary circuit for relay H^3 does not include the corresponding back contact of relay H^2 .

When relay H^2 is energized in the normal direction, the proceed lamp G of this signal is lighted by virtue of a circuit which passes from terminal B, through the front point of contact 14 of relay R^2 , polar contact 12 of relay H^2 in the left-hand position, and the proceed lamp G of signal S^x to terminal O. When relay H^2 is energized in the reverse direction, the caution lamp Y is lighted, the circuit being the same as before, except that it includes polar contact 12 in the right-hand position, and, of course, it includes the caution lamp Y. When relay H^2 is de-energized, relay R^2 is also de-energized, and the stop lamp R of signal S^x is then lighted by virtue of a circuit which includes this lamp and the back point of contact 14 of relay R^2 . The lamps of signal S^y are controlled in a similar manner by contact 21 of relay R^3 and polar contact 19 of relay H^3 .

65. The operation of the apparatus is as fol-

lows: We will first assume that a train moving toward the right enters the approach section W—X, thereby de-energizing track relay T^1 . This will open the circuit for line relay H^3 at contact 4, so that signal S^y will immediately assume the stop indication. We will now assume that while section W—X is occupied by a first train, a second train moving toward the left enters the approach section Y—Z. In accordance with previous practice, this would cause signal S^x to assume the stop indication, so that the first train would have to stop at point X prior to entering siding A. Owing, however, to the auxiliary circuit for relay H^2 , the entrance of the second train into section Y—Z will cause relay H^2 to become energized in the reverse direction, thereby causing signal S^x to give a caution indication, with the result that the train in section W—X may proceed into the siding A without the necessity for stopping at point X.

Similarly, if a train moving toward the left enters section Y—Z while the other approach section is unoccupied, the opening of track relay T^4 will open the circuit of line relay H^2 , so that signal S^x will give the stop indication. If then, a second train enters section W—X moving toward the right, the auxiliary circuit for relay H^3 will become closed, with the result that signal S^y will give the caution indication, thereby permitting the train moving toward the left to enter the siding A without stopping at the point Y.

The reason for including back contact 17 of relay H^3 in the auxiliary circuit for relay H^2 is as follows: We will assume that one train is in section X—Y and a following train is in section W—X; then when the first train advances into section Y—Z, relays H^2 and H^3 will both pick up at the same time, and this will tend to pick up both relays R^2 and R^3 at the same time, with the result that the circuits for relays H^2 and H^3 would be opened. This would be likely to cause a "bobbing" action of the line relays. Owing to the fact that contact 17 of relay H^3 is included in the auxiliary circuit for relay H^2 , the circuit for relay H^2 will be opened as soon as the back contact of relay H^3 opens, thereby eliminating the possibility of the bobbing action just referred to.

Although we have herein shown and described only one form of apparatus embodying our invention, it is understood that various changes and modifications may be made therein within the scope of the appended claims without departing from the spirit and scope of our invention.

Having thus described our invention, what we claim is:

1. In combination, a stretch of single track railway provided with a passing siding, signals at each end of said siding governing

traffic through the siding, means normally responsive to a train approaching the siding from either direction for causing the opposing signal to indicate stop, and means for preventing a second train approaching the siding from causing the opposing signal to indicate stop when a first train is already approaching the siding from the other direction.

10. 2. In combination, a stretch of railway track provided with a passing siding, a signal governing traffic in one direction through said siding, means normally responsive to a train moving in the other direction and approaching said siding for causing said signal to indicate stop, and means for preventing such train from causing said signal to indicate stop when another train moving in the direction governed by the signal is already approaching the siding.

15. 3. In combination, a stretch of single track railway provided with a passing siding, signals at each end of said siding governing traffic through the siding, means normally responsive to a train approaching the siding from either direction for causing the opposing signal to indicate stop, and means responsive to a second train approaching the siding for causing the opposing signal to indicate caution when a first train is already approaching the siding from the other direction.

20. 4. In combination, a stretch of railway track provided with a passing siding, a signal governing traffic in one direction through said siding, means normally responsive to a train moving in the other direction and approaching said siding for causing said signal to indicate stop, and means responsive to the approach of such train for causing the signal to indicate caution when another train moving in the direction governed by the signal is already approaching the siding.

25. 5. In combination, a stretch of single track railway provided with a passing siding, signals governing traffic from opposite directions into said siding, an approach section at each end of said siding, means normally responsive to the entrance of a train into either of said sections for causing the opposing signal to indicate stop, and means for preventing a second train entering one of said sections from causing the opposing signal to indicate stop when a first train already occupies the other section.

30. 6. In combination, a stretch of single track railway provided with a passing siding, signals governing traffic from opposite directions into said siding, an approach section at each end of said siding, means normally responsive to the entrance of a train into either of said sections for causing the opposing signal to indicate stop, and means responsive to a second train entering one of said sections for causing the opposing signal

to indicate caution when a first train already occupies the other section.

35. 7. In combination, a stretch of single track railway provided with a passing siding, an approach section at each end of said siding, a track circuit including a track relay for each approach section, a line relay for each end of said siding, a normal circuit for each line relay controlled by a front contact of the approach section track relay at the other end of the siding, an auxiliary circuit for each line relay controlled by a back contact of the approach section track relay at the other end of the section and also by the other line relay, and signals for said siding controlled by said line relays.

40. 8. In combination, a stretch of single track railway provided with a passing siding, an approach section at each end of said siding, a track circuit including a track relay for each approach section, a line relay for each end of said siding, a repeater relay controlled by each line relay, a normal circuit for each line relay including a front contact of the track relay of the approach section at the other end of the siding, an auxiliary circuit for each line relay including a back contact of the track relay of the approach section at the other end of the siding and a back contact of the line repeater relay at such other end of the siding, and signals for said siding controlled by said line relays.

45. 9. In combination, a stretch of single track railway provided with a passing siding, an approach section at each end of said siding, a track circuit including a track relay for each approach section, a line relay for each end of said siding, a repeater relay controlled by each line relay, a normal circuit for each line relay including a front contact of the track relay of the approach section at the other end of the siding, an auxiliary circuit for each line relay including a back contact of the track relay of the approach section at the other end of the siding and a back contact of the line repeater relay at such other end of the siding, the auxiliary circuit for one line relay including also a back contact of the other line relay, and signals for said siding controlled by said line relays.

50. 10. In combination, a stretch of single track railway provided with a passing siding, an approach section at each end of said siding, a track circuit including a track relay for each approach section, a pole-changing relay controlled by each track relay, a line relay for each end of said siding, a repeater relay controlled by each line relay, a normal circuit for each line relay including a front contact of the track relay of the approach section at the other end of the siding, an auxiliary circuit for each line relay including a back contact of the track relay of the approach section at the other end of the siding and a back contact of the line

repeater relay at such other end of the siding, means for supplying current of normal or reverse polarity to the circuits for each line relay according as the pole-changing relay at the opposite end of the siding is energized or de-energized, and a siding signal controlled by each line relay and arranged to indicate proceed or caution according as the relay is supplied with current of normal or reverse polarity.

In testimony whereof we affix our signatures.

HENRY S. YOUNG.
CHARLES A. BROOKS.
